Inventor,
Ralph M. C. R. August,
By his Attorney,
H. B. Hutchinson.

UNITED STATES PATENT OFFICE.

RALPH M. C. R. AUGUST, OF GREAT KILLS, NEW YORK, ASSIGNOR, BY MESNE ASSIGNMENTS, TO L. A. FLORENCE, OF TEANECK, NEW JERSEY.

RADIOJACK.

Application filed February 3, 1925. Serial No. 6,580.

My invention relates to improvements in radio jacks or radio switches so called, which is in effect a simple form of jack or switch. The object of my invention is to produce a 5 very cheap, simple, exceedingly effective jack having its contacts arranged so as to produce a structure of the low capacity class in which the contacts instead of having their broad sides opposed, are arranged edge to edge. The invention is also intended to produce a structure which while exceedingly effective, is much cheaper than the ordinary and to this end I make the insulating body of such shape that it can be readily 10 molded of hard rubber or other suitable insulating substance. Furthermore, I can mold a body of this kind with a middle slot having inclined walls which serve as a substantial and yet simple and inexpensive 15 guide for a plug. My invention is also intended to produce a very simple and effective jack which can be cheaply and securely attached to a supporting panel, and in which the means of attachment also serves as a 20 guide to the jack plug. These and other advantages will appear more clearly from the 25 description which follows.

Reference is to be had to the accompanying drawings forming a part of this specification, in which similar reference characters indicate corresponding parts in all the 30 views.

Figure 1 is a plan of the jack embodying my invention.

Figure 2 is a longitudinal section thereof.

Figure 3 is a plan of a slightly modified form of jack, and

Figure 4 is a cross section of the jack shown in Figure 3.

The structure is provided with an insulating body 10 which is preferably flat and rectangular, but which irrespective of its general contour is provided with a central slot 11 extending from near one end of the body to the other end edge thereof, forming a fork-like body, and this slot has inclined walls 12 which make it serve nicely as a guide for the plug hereinafter referred to. The general fork shape of the jack body 45 with its slot as described, is important because in many structures of this kind the body has to be bored out or molded in an expensive way, whereas in the form shown 50 the shape is so simple and so easy to form

that a very cheap and effective body can be 55 produced.

The open end of the jack body is attached to a support, as for instance a panel, by means of a bracket plate 13 which is formed with straps 14 adapted to fit against one side 60 of the jack as shown clearly in Figures 1 and 2, and screw bolts 15 extending through the jack body and straps 14 serve to firmly unite the body and straps, and the union is stronger because the end of the body fits 65 snugly against the bracket plate 13. This plate 13 also abuts on its inner side with the flange 16^a of a bushing 16 which is adapted to extend through the panel 17 or similar support, and the outer part is screw threaded as shown at 18 so as to receive the fastening nut 19, and thus the jack can be easily 70 put in place and firmly secured, as the panel will be gripped between the abutting bracket plate 13 and the nut 19 as shown in Figure 2. 75

With a body of this kind it is a simple thing to attach the contacts so that they will lie substantially edge to edge, and thus come within the low capacity class of jacks. As shown in Figures 1 and 2 I have provided 80 crossing contacts 20 and 21 which are separated at the point of crossing by insulation 22, and which are secured at one end by screw bolts 23 and 23^a which at the opposite side may be connected up as desired, and the 85 free ends of the spring contacts 20 and 21 abut with the contact screws 24 and 24^a, which also may be connected as desired.

Spaced apart from these contact springs 20 and 21 and like them lying flatwise on 90 the jack and across the slot 11, is another contact spring 25 which is secured by a screw bolt 26 extending through the jack body, and contacts with a screw bolt 27 on the opposite side of the body. I have not referred 95 to the connections of these contacts, because obviously they may be the usual or any preferred connections, but the important thing is that they are arranged with their edges opposite each other and in such a way that 100 they normally make contact with their respective contact screws, but can connect as usual with the plug 27^a which moves as usual longitudinally of the jack, and has the customary or any preferred connections. 105

In Figures 3 and 4 I have shown a slightly different arrangement of contacts in which instead of the crossing contacts 20 and 21,

I substitute a flat contact spring 31 which is secured to the body 10 by a screw bolt 32 which can be connected in any preferred way, and at the free end the contact spring 5 can contact with a screw bolt 33 which likewise can be connected as desired. Parallel with the flat contact 31 is a flat contact spring 34 which is spaced apart from it and connected with a screw bolt 35, passing 10 through the body 10, while its free end contacts with a screw bolt 36 which may be connected as desired.

The plug 27¹ as shown is a conventional plug, and is only referred to in a general 15 way as it has the customary means for connections. At its inner end it has a knob 28 to contact with a spring contact 20 or 31 as the case may be, and the knob is insulated from the body of the plug as shown 20 at 29, and has the internal insulated stem 29¹ as usual. It also has the customary or any preferred head 30 through which the 25 connections are made with the stem 29¹ or body of the plug, as desired. The means for making these connections is not new, and is so well known that said means is not illustrated, the important feature of this invention being the structure of the body 10 to 30 enable it to be cheaply and easily made, the means for attaching it to a panel, and guiding the plug, and the arrangement of the flat contacts edge to edge on the slotted body.

I claim:—

1. A device of the kind described comprising a jack having a recessed body, the walls of said recess being inclined, spring contacts crossing the recess transversely thereof, and a plug movable in the recess and guided by said inclined walls and arranged 40 to contact with the aforesaid spring contacts.

2. A device of the kind described comprising a jack having a longitudinally slotted body, contact springs arranged edge to edge 45 and crossing the slot of the body transversely thereof, means for securing the body on a support, and a plug sliding in the slot and engaging the contact springs.

3. A device of the kind described comprising a jack having a longitudinally slotted body with the walls of the slot inclined, flat contact springs arranged edge to edge and extending across the body, and a plug movable 50 in the slot and guided on the aforesaid

inclined walls, said plug being arranged to 55 make contact with the contact springs.

4. A device of the kind described comprising a jack having a flat slotted insulating body with inclined walls for the slot, contact springs secured on the body and 60 crossing the slot, said contact springs being arranged edge to edge, and a plug guided on the inclined walls of the slot and arranged to engage the contact springs.

5. A device of the kind described comprising a jack having a longitudinally slotted body, a bracket connected to one end of the body and provided with a bushing threaded to receive a nut, and a plug 65 slideable through the bushing and into said 70 slotted body for contacting with the aforesaid contact springs.

6. A device of the kind described comprising a jack having a flat insulating bifurcated body, the walls to the slot having 75 inclined contact springs arranged edge to edge and spanning the slot, a bracket at the open end of the body having means for attachment to the body, a threaded bushing connected with the bracket and adapted to 80 extend through a support and receive a nut, and a plug slideable through the bushing and on the inclined walls of the slotted body, said plug connecting with the aforesaid contact springs. 85

7. A device of the kind described comprising a jack having a flat bifurcated insulating body with inclined walls to the slot therein, flat contacts spaced apart and spanning the slot, said contacts being 90 arranged edge to edge, a plug slideable in the slot and guided by said inclined wall to make connection with said contacts, and means for securing said body to a support 95 panel.

8. A flat slotted insulating radio jack body having flat contacts edge to edge crossing the slot of the body transversely thereof.

9. A flat slotted insulating radio jack 100 body, spaced flat contacts crossing the slot of the body transversely thereof and arranged edge to edge, and means for securing the body endwise to a support.

In testimony whereof, I have signed my name to this specification this 29th day of January, 1925. 105

RALPH M. C. R. AUGUST.
